ADJUSTABLE BENDING BRAKE WITH WORK CLAMP LATCHING MEANS

William C. Tiff, Seymour, Conn., and Jacob F. Kreissig, Frederick, Md., assignors to Frederick Iron and Steel, Inc., Frederick, Md., a corporation of Maryland

Application January 20, 1948, Serial No. 3,306

7 Claims. (Cl. 153—16)

1

This invention comprises novel and useful improvements in an adjustable sheet metal bar folder and has for its primary object the provision of a machine for forming marginal folds, bends or flanges in metal sheets, of predetermined widths and through various arcs of bending.

An important object of this invention resides in providing an apparatus for bending metal sheets to form marginal flanges of predetermined and widely varied width.

A further object is to provide an apparatus in accordance with the preceding object which is capable of forming bends of any predetermined extent including substantially complete 360° bend.

Still another important object of the invention resides in the provision of an apparatus which automatically and positively clamps the sheet to be bent to the anvil before the application of any substantial bending movement thereto; and which automatically releases the clamping action as the folder is returned to its inoperative position.

A still further object of the invention, in conformity with the preceding objects, is to provide an apparatus having margin determining means for positively limiting the width of the margin of a sheet to be bent and which is incapable of interference with or of hindrance by the clamping means.

Still another important object of the invention is to provide an apparatus which is easily adjustable to accommodate sheets of different thicknesses for bending.

Yet another important object of the invention resides in providing an anvil, a folding carriage, clamping means for securing a sheet to the anvil, latch means for positively locking the clamping means into clamped position, together with automatic means for controlling the clamping means and the latching means in synchronized relation to each other and for actuation by the folding carriage.

Yet another essential object of the invention resides in the provision of an apparatus as set forth in the preceding objects wherein the fold regulating means is guided to move always in parallelism throughout its entire range of adjustment.

Yet another object of the invention is to provide an apparatus as set forth in the preceding objects means for adjustably limiting the amplitude or extent of the bending movement as desired.

And a final important object of the invention

to be specifically enumerated herein, resides in the provision of an apparatus as set forth in the preceding objects which shall be of compact construction, durable and efficient, and with all of relatively light weight, portable and inexpensive.

These, together with various ancillary objects of the invention which will later become apparent as the following description proceeds, are attained by this device, a preferred embodiment of which has been illustrated by way of example only in the accompanying drawings, wherein:

Figure 1 is a perspective view of the rear of the machine;

Figure 2 is a perspective view of the front of the machine, with the carriage in its raised position for bending a sheet of metal;

Figure 3 is a perspective view of the sheet clamping means forming a part of the invention, shown detached from the machine;

Figure 4 is a vertical transverse sectional view through the machine, parts being shown in elevation, the mechanism being shown in its rest position and is taken substantially upon the plane of the section line 4—4 of Figure 1;

Figure 5 is a vertical sectional view through the machine, parts being broken away, taken substantially upon the plane of the section line 5—5 of Figure 1, the parts being in the position shown in Figure 4;

Figure 6 is a vertical sectional view through the machine illustrating the operation of certain parts thereof, with the movable jaw illustrated in its closed position and the latching means engaged therewith;

Figure 7 is an end elevational view of the device, parts being broken away and alternative positions of a stop means being indicated in dotted lines;

Figure 8 is a vertical transverse sectional view through the machine, illustrating its use in forming a bend in a sheet of metal; and,

Figure 9 is a horizontal sectional detail view, illustrating the construction of an adjusting mechanism for regulating the amount of bending performed by the machine, and is taken substantially upon the plane of the section line 9—9 of Figure 7.

In order that the purposes, construction and advantages of this machine may be more readily understood, it is here noted that it is frequently necessary to form marginal bends, folds or flanges upon the edges of sheet metal strips for various purposes such as to secure marginal wires or cables thereto; to provide flanges at various angles to the sheet for a multitude of

commercial uses. It is extremely desirable that there be provided an apparatus for performing these bending operations, and a prime requisite of such an apparatus is that the same shall be portable, easily adjusted to accommodate various thicknesses of sheets of material, may be readily adjusted to form with certainty marginal folds of predetermined width; and which may be quickly set to effect bending movements throughout various predetermined arcuate extent. It is also highly desirable that clamping means shall be provided for rigidly securing the sheet to be bent to the anvil of the machine, and that there shall be no danger of slippage of this clamping means; and yet that the clamping means shall be automatically released in returning the operating part of the machine to its original or rest position.

Moreover, it is highly essential that the stop mechanism for regulating and determining the width of the marginal portion of the sheet to be folded shall have true rectilinear motion to maintain a parallel relation of the fold of the sheet to its marginal edge throughout all positions of adjustment.

The present invention efficiently attains the above objects and the above requisites by providing a stationary anvil about which a sheet is to be bent, and providing a swinging or pivotal carriage for conveying the main portion of the sheet about the anvil in an arcuate movement; by providing a removable clamping jaw for engaging the marginal edge of the sheet and affixing the same rigidly to the anvil; by providing spring means for normally urging the movable jaw into its clamping position and by providing automatic means for retracting the movable jaw when the bending carriage is returned to substantially its original or rest position; by providing an automatic latch means for positively locking the movable jaw into its clamping position at the beginning of the bending operation, which latch means is automatically withdrawn immediately prior to the releasing of the movable jaw by the carriage return movement. There is further provided a slidably adjustable finger assembly constituting a stop for engagement by the marginal edge of a sheet for thus determining the width of the flange to be folded on the edge of the sheet, which stop is positively guided for movement to and from the bending carriage and is at all times parallel with the bending edge of the anvil.

Referring now more specifically to the accompanying drawings, wherein like numerals designate similar parts throughout the various views, there is disclosed by way of example of the principles of the invention, but in no way of the limitation thereof, a satisfactory embodiment of a mechanism constructed in accordance with the foregoing objects, requisites and advantages.

Frame construction of the machine

As shown best in the rear view of Figure 1 and the front view of Figure 2, the machine includes a frame designated generally by the numeral 10 which preferably comprises a hollow casting forming a housing or casing to which are attached and within which are housed the various elements and operating instrumentalities to be hereinafter set forth. The frame includes end walls 12 and a bottom plate, bed or base 14. Suitable lugs or brackets 16 comprise means for supporting the frame and for securing the same to any satisfactory support, it being here empha-

sized that the machine is intended to be of a portable nature.

The frame is further provided with a closed vertical back wall 18 and a top wall 20, which, as shown best in Figures 4, 5 and 8, is provided with a longitudinally extending recess or seat 22 for receiving an anvil 24 thereon. This anvil is preferably provided with a forwardly extending bevelled nose 26 forming a knife edge and constitutes the surface about which a sheet of metal is to be folded. As shown in Figure 1, the anvil is detachably secured to the top wall 20 as by means of a plurality of fastening bolts 28, whereby the anvil is positioned for ready removal from the device for any necessary servicing, or for replacement by a substitute anvil of any desired shape or contour as when forming bends having various predetermined characteristics.

As shown best in Figure 2, end walls 12 are provided with laterally extending bosses 30 at their upper ends and rearwardly of the end walls 12, which bosses are drilled or apertured to provide journal receiving axle pins 32 by means of which the carriage assembly indicated generally at 34 is hingedly and pivotally mounted upon the frame of the machine. As may be best seen by Figures 4, 5 and 6, the frame 10 is thus open at its front end below the anvil 24 for the reception of a mechanism to be subsequently set forth, this opening extending longitudinally of the frame between the two end plates 12 thereof, while the frame is further provided adjacent its rear wall with a chamber opening upwardly from the bottom surface of the bed plate 14, this chamber being indicated at 84.

The carriage assembly

The carriage assembly 34 as shown in Figure 2 is of somewhat greater length than the frame member 10 and is provided at its extremities with laterally extending lugs 36 which embrace the end walls 12 and by means of which the carriage assembly is pivoted to the axle pins 32. These axle pins are rigidly attached to the lugs 36, and extend through the bosses 30, and have a pair of clamp operating cams 38 rigidly fastened to the inner ends of the pins 32 whereby these cams are rotated as the carriage assembly is pivotally raised or lowered.

At each end, the carriage assembly is provided with enlarged handle sockets 40, either of which may detachably receive an operating handle 42, by means of which the carriage assembly may be pivoted about the axle pins 32 for raising and lowering of the same as set forth hereinafter.

As shown best in Figure 5, each of the handle sockets 40 has pivoted thereto as by fastening screws 44, a pair of arms 46 which at their inner extremities support the transversely extending folder bar 48, having a flat upper surface 50 which as shown in Figure 5, is disposed in a plane which is substantially parallel to the plane of the upper surface of the tapered portion 26 of the anvil 24. Journalized in the carriage assembly 34, and extending through one of the end lugs 36 thereof, is a longitudinally extending shaft 52 provided with a knurled operating head 54 on the exposed end thereof. This shaft is provided with a plurality of eccentrically disposed operating cams or eccentrics 56 which are engageable with depending operating lugs 58 carried by the folder bar 48, whereby upon rotation of the shaft, the cam members cause an oscillation of the folder bar about its pivot point 44. One or more journals 60 are provided in the carriage assembly to

provide bearings for the shaft 52, which journals may be of any suitable and desired construction. Preferably, a lock screw 62 having a knurled head to provide a finger grip portion, extends through the normally upright wall of the carriage 34, and has its end disposed for engagement with the shaft 52, whereby the latter may be locked in any desired position of adjustment. Thus, by releasing the said screw 62, the adjusting shaft 52 may be rotated by the thumb grip portion 54, causing the cams 56 to raise or lower the folder bar 48 relative to the knife edge portion 26 of the anvil. This adjustment is for the purpose of accommodating different thicknesses of sheet metal which it is desired to bend in the device, and also for regulating the radius of bend within the range of adjustment as set forth hereinafter.

Stop lugs are formed upon the inner edge of the carriage assembly 34, for abutting engagement with the edge of the bottom plate 14 when the carriage is in its idle or rest position, as shown in Figure 5. These lugs thus serve to support the carriage in its rest position while a sheet of material is applied or removed from the device as set forth hereinafter.

As will be further apparent from Figures 2 and 6, the carriage is provided with a plurality of screw threaded bolts or studs 66, which extend through the carriage and protrude from both the inner and outer surfaces thereof, these screw threaded members being provided with lock nuts 68, whereby the studs or bolts may be adjustably protruded from the inner surface of the carriage member and locked in adjusted position for a purpose which will be later apparent.

Movable clamp jaw assembly

Pivoted secured to the frame 10 in the above mentioned cavity or recess in the front wall of the frame, is a movable clamp jaw 70 which as shown in Figures 2 and 5, is a flat bar extending substantially the entire length of the space between the two end walls 12 of the frame 10, and which is pivotally mounted therein for oscillatory movement into and out of clamping engagement with the lower surface of the knife portion 26 of the anvil 24.

This movable clamp jaw comprises means for releasably securing the edge of a sheet of metal which it is desired to bend, to the undersurface of the anvil, whereby the remainder of the sheet may be bent about the knife edge 26 to form the crease or fold.

The upper or clamping surface of the movable jaw is provided with a plurality of notches 72 providing clearance for a purpose which will subsequently become apparent. As shown most clearly in Figures 2, 5 and 8, a plurality of coil springs 74 are seated upon the bed plate 14 and at their upper ends are seated in sockets 76 formed in the lower surface of the movable jaw 70. These springs normally urge and bias the clamp jaw 70 into its upper and closed position against the under side of the anvil 24, thereby resiliently clamping a metal sheet therebetween. A pair of support arms 78 (see Figure 6) are integrally formed and extend rearwardly from the movable jaw, for supporting the jaw for pivotal movement about a fulcrum pin 80 which is suitably mounted in the above mentioned cavity or chamber 84 in the frame 10. These support arms 78 extend through slots 82 in the frame 10, these slots providing the necessary clearance to permit the oscillation of the support arms 78 about the pins 80. Extending axially from the

lower end of the movable jaw 70, are a pair of pintles 86 upon which are rotatably mounted a pair of rollers 88 which are positioned for engagement by the operating cam 38 above mentioned. It will thus be seen from Figure 6 that as the carriage 34 is rotated about its axle pins, the cams 38 will be likewise rotated to selectively engage or withdraw the cam surface from the rollers 88, thereby depressing the movable jaw 70 against the action of the closing springs 74, or releasing the same. Obviously, the cams 38 will be appropriately positioned upon the axle shaft 32 to cause the appropriately timed release of the movable jaw whereby the springs 74 may close the same; and the correspondingly timed engagement of the roller by the cams 38 whereby the latter upon predetermined opening movement of the carriage will force the jaw to its open position against the action of the closing springs 74.

It will thus be seen that various and automatic and predetermined timed operating connections between the carriage 34 and the clamping jaw 70, are provided whereby the single movement of the carriage will serve to first release the jaw and permit the same to yieldingly clamp a piece of sheet metal between the movable jaw and the anvil, and upon subsequent movement of the carriage will then apply a bending movement to the sheet to cause the desired marginal flange or fold thereon.

Jaw latching assembly

In order to insure that the movable jaw when once closed upon a sheet of metal will not be unintentionally opened by the force applied thereto as the metal is bent by the continued movement of the carriage, there is provided a latch means for positively locking the jaw into its closed position, this latch means being automatically controlled by the position of the carriage. For this purpose, the lower surface of the movable jaw is provided with a plurality of cam surfaces 90 which are engageable by the correspondingly shaped inclined surfaces of wedges 92 formed upon latch pins 94 and slidably transversely of the frame and jaw. These pins 94 are slidably received in guide bosses 96 carried by the frame and at their latching ends extend forwardly of the frame for engagement by the above mentioned adjusting screws 66, while their other extremities extend into the chamber 84 which provides clearance for the movement of the latch pins. A coiled spring 98 surrounds the latch pin and bears against the above mentioned bosses 96, and against the rear surface of the wedge 92, to thereby yieldingly urge the latch pins and wedges into their operative or latching position, at which time the inclined surface of the wedge 92 will rest upon and bear upwardly against the inclined cam surfaces 90 of the movable jaw.

From the foregoing, it will be seen that as soon as the movable jaw is moved upwardly in position to clear the forward end of the wedges 92, the latter will be urged by the springs 98 into wedging and locking action beneath the surfaces 90, thereby resisting any downward movement of the jaw until the latches shall have been withdrawn by engagement and inward movement of the operating screws 66 when the carriage 34 is in its open position. Preferably, the adjusting screws 66 are so positioned with respect to the position of the cam 38, that the following timed operating relation exists.

When the carriage is at its fully open position,

as shown in Figure 5, the latch pins 94 are held in their released position against the action of the springs 98 by engagement of the latch screws 66, during which position, the stop lugs 64 are engaging the forward edge of the bed plate 14 as shown in Figure 5. At the same time, the cam 38 has engaged the rollers 88, and has urged the movable jaw 70 into its lowermost position, against the action of the closing spring 74, whereby there is a clearance between the upper end of the movable jaw 70 and the lower surface of the anvil 24, as shown in Figure 5, and whereby a metal sheet may be inserted between the anvil and movable jaw. As the carriage is now moved upwardly by the handle 42, the adjusting bolts 66 are withdrawn from the end of the latch pins 94 and the cam 38 begins to withdraw from the roller 88 as shown in Figure 6. This withdrawal of the cam from the roller permits the spring 74 to begin to raise the movable jaw 70 until the latter is resiliently clamped upon a sheet of metal placed thereon. As soon as the movable jaw has raised a sufficient distance, the wedges 92 are driven therebeneath by the springs 96, and at this point return movement of the jaw is impossible until these locking wedges are positively released by the downward movement of the carriage at engagement of the locking bolts 66. Further upward movement of the carriage now raises the body of the metal sheet, causing a bend about the knife edge 26, as the fold or margin of the metal sheet is clamped to the undersurface of the anvil. The extent of this bend will of course depend upon the amount of angular rotation imparted to the carriage 34 by rotation of the same about its axle pins 32 by the handle 42.

On the releasing or return movement of the carriage, to its lower or rest position, the adjusting screws 66 first engage the latch pin 94 and force the withdrawal of the same from beneath the movable jaw; and thereafter the cam 38 engages the roller 88, thus depressing the movable jaw against the spring 74.

Stop finger assembly

In order to provide even margins or flanges on the sheet to be folded, an adjustable stop is necessary to properly position the marginal edge of the metal sheet in the device. This stop assembly, which is shown in its entirety in Figure 3, and of which structural details are disclosed in Figures 4, 5 and 8 in different positions of adjustment, consists of a finger assembly frame 100 preferably comprising a flat plate disposed longitudinally of the cavity in the front wall of the frame 10, and positioned behind the movable jaw 70. At its upper extremity, the assembly frame 100 is provided with bifurcated upwardly extending lugs 102 between which bifurcations are received the rearwardly extending edge lugs 104 of the finger bar 106 which is pivoted thereto as by pins 108. The plate 100 is positioned generally vertical, while the finger bar 106 and the fingers carried thereby are positioned generally horizontal.

Spring means such as a resilient metallic strip 110 is secured to the frame 100 and against finger bar 106, for resiliently urging the finger bar and the fingers thereby upwardly about their fulcrum or pivot pins 108. These fingers indicated generally by the numeral 112, preferably comprise forwardly extending rods 114, whose outermost extremities are upwardly turned as at 116. The extremities 116 are preferably posi-

tioned in a vertical plane which is parallel to that of the frame 100.

Secured to the ends of the bar 106 are indicators 118 cooperating with scales 164, see Figure 1, for indicating the spacing of the fingers 112 from the folding edge of the knife 26.

Secured centrally and extending rearwardly of the frame 100, is a tubular sleeve 120 provided with an internally threaded bore, which sleeve is slidably received in a guide bore 122 see Figure 8, which guide bore communicates with the interior of the chamber 84 above mentioned. An adjusting screw 124 provided with an operating knob 126, extends through the rear wall 18 of the frame, and is screw threadedly engaged in the bore of the sleeve 120, whereby the sleeve and the attached frame 100 with the finger bar, may be moved rearwardly for adjusting the fingers with respect to the knife edge.

Depending from the lower portion of the frame 100, are a pair of lugs 128 constituting journal bearings for rotatably receiving a shaft 130 extending longitudinally of the plate, which shaft at its extremities is provided with gears 132, each of these gears engaging a rack bar 134 rigidly secured in any suitable manner to the frame 10. These rack bars and gears provide guiding means for maintaining the parallel arrangement of the finger assembly as the latter is adjusted laterally to and from the knife edge 26. Also extending rearwardly and integrally attached to the frame 100, are a pair of tubular sleeves 136 (see Figure 4) constituting guide means which are slidably received in guide bores 140 communicating with the interior of the chamber 84. Coil springs 138 are positioned in the sleeves 136, and abut against the inner surface of the rear wall 18, to yieldingly urge the finger assembly forwardly with respect to the knife edge 26 of the anvil 24.

The fingers 112 are positioned to be slidably received in the notches 72, with the upper ends 116 of the fingers pressed against the lower surface of the anvil 24, and yieldingly urged thereagainst by the spring means 110.

It will thus be seen that in both the forward position of the finger assembly, as shown in Figures 4 and 5, the notches 72 provide sufficient clearance whereby the movable jaw 70 will not interfere with movement of the fingers while the latter will not prevent the closing movement of the jaw. The adjusted position of the finger assembly rearwardly of the movable jaw is shown in Figure 8, where it will be seen that the end 168 of the sheet metal strip 166 is abutted against the front portion of the series of finger pins 116, while the upper surface of the movable jaw clamps this marginal portion of the strip tightly against the undersurface of the anvil, while the rest of the strip is folded or bent around the knife edge 26 of the anvil.

It will be particularly noted that by reason of the notches 72, the stop finger assembly can be readily adjusted without necessitating any movement of the movable jaw 70, if this is desired; while in all positions of adjustment of the stop fingers, free operation of the movable jaw is permitted.

Adjustable folder stop

In order to enable the operator to readily form a bend of any desired number of degrees of arcuate movement of the carriage, an adjustable stop mechanism is provided. This mechanism as indicated in Figure 2 and shown best in Figures 7 and 9, includes a lug 142 carried by one of

the end walls 12 of the frame 10, which lug constitutes an abutment provided with an adjusting screw 144 having a lock nut 146. A stop lug 148, adapted to engage the adjusting screw 144, is carried by a collar 150 loosely received on the carriage axle 32 between the boss 38 and the end bracket 36 of the carriage. As indicated in dotted lines in Figure 7, the collar 150 is provided with a plurality of sets of diametrically opposite bores 152 constituting locking recesses. A pair of locking pins 154 carried by a locking pin plate 156 provided with a finger grip knob 158, are slidably received within, and extend through bores 152 formed in the member 36, and have their ends extensible into the locking recesses 152. A coil spring 160 surrounds a stem 161 formed axially on the plate 156, the spring and stem being received in a bore or axial recess 162 formed in the end of the carriage axle 32. This spring is so positioned as to urge the plate 156 and the locking pins 154 into their inward or locking position as shown in Figure 9. In order to change the position of the collar 150 with respect to the carriage, and thereby change the position of the carriage when the movement of the same is limited by engagement of the lug 143 with the stop member 144, it is only necessary to withdraw the pins 154 against the opposition of spring 160 to release the ends of the pins from the locking recesses 152, whereupon the collar 150 may be turned until another pair of recesses may be aligned with the pins. As will be readily understood, a plurality of these recesses will be provided, the relative positions of these recesses being such that any desired angular movement may be imparted to the carriage before the stops engage for limiting further movement. Thus, a series of the most frequent angular bends which it is desired to perform upon the machine may be readily attained by the easy use of the proper stop.

Referring now to Figure 5, it will be seen that by manipulation of the knob 126, the stop finger assembly may be retracted to permit a portion of the edge of a sheet of metal to be inserted between the jaw 70 and the anvil 24, the width of the margin so inserted being determined by the relative position of the stop finger assembly. One such position is shown in Figure 8, where it will be seen that this sheet 166 and its marginal edge 168 abutting the stop fingers 112, and the body portion of the sheet 166 has been fitted about the knife edge 26 by the upward movement of the holder bar 43 and carriage 34 to form a substantially perpendicular flange upon the sheet. Obviously this flange could be bent further until almost a complete 360° bend was effected, or until the folding stop was engaged.

From the foregoing, the construction, operation and advantages of the invention will be readily understood and further explanation is believed to be unnecessary. However, since numerous changes and modifications will readily occur to those skilled in this art after a consideration of the principles of the invention as set forth in the foregoing specification and annexed drawings, it is not intended to limit the invention to the exact construction shown and described, and accordingly all suitable modifications and equivalents may be resorted to falling within the scope of the appended claims.

Having described the invention, what is claimed as new is:

1. A sheet metal folder comprising a frame provided with an anvil having a metal bending

surface, a movable jaw for clamping a metal sheet to said surface, a metal bending carriage pivoted to said frame, a folder bar on said carriage, mechanism connecting said carriage and said movable jaw for opening and closing movement of the latter in timed relation to movement of said carriage, rectilinear reciprocable latch means for said movable jaw and latch actuating means operable in timed relation to movement of said carriage, said latch means including locking cams slidably beneath said movable jaw for preventing opening movement thereof, springs urging said cams into locking position, latch releasing bolts on said carriage, said bolts being positioned to release said latch means in timed relation to movement of said carriage and said movable jaw.

2. A sheet metal folder comprising a frame provided with an anvil having a metal bending surface, a movable jaw disposed beneath said anvil for clamping a metal sheet to said surface, a metal bending carriage pivoted to said frame and having a folder bar thereon, resilient means urging said movable jaw towards said bending surface, latch wedge guides on said frame, latch wedges mounted in said guides and slidably transversely of said movable jaw, latch surfaces on said movable jaw engageable by said latch wedges when the movable jaw has been urged towards said bending surface by said resilient means for locking said movable jaw in clamping position upon said bending surface, latch wedge retracting means on said carriage moving said wedges out of engagement with said latch surfaces when said carriage is in its idle position and actuating means operable to move said movable jaw against said resilient means upon movement of said carriage away from said bending surface.

3. The combination of claim 2 wherein said wedge surfaces extend longitudinally of said frame and said latch wedges and guides extend transversely thereof.

4. The combination of claim 2 wherein said wedge surfaces extend longitudinally of said frame and said latch wedges and guides extend transversely thereof, and are both disposed below the bottom of said movable jaw, said wedges having actuating pins projecting beyond one end thereof for engagement by said retracting means.

5. The combination of claim 2 wherein said wedge surfaces extend longitudinally of said frame and said latch wedges and guides extend transversely thereof, and are both disposed below the bottom of said movable jaw, said wedges having actuating pins projecting beyond one end thereof for engagement by said retracting means, a guide pin projecting beyond the other end of each wedge, guide means in said frame for each guide pin.

6. The combination of claim 2 wherein said wedge surfaces extend longitudinally of said frame and said latch wedges and guides extend transversely thereof, and are both disposed below the bottom of said movable jaw, said wedges having actuating pins projecting beyond one end thereof for engagement by said retracting means, a guide pin projecting beyond the other end of each wedge, guide means in said frame for each guide pin, a spring surrounding each guide pin and urging its latch wedge into latching position with its latch surface.

7. The combination of claim 2 wherein said wedge surfaces extend longitudinally of said frame and said latch wedges and guides extend transversely thereof, and are both disposed below the bottom of said movable jaw, said wedges hav-

ing actuating pins projecting beyond one end thereof for engagement by said retracting means, said retracting means including a member adjustable upon said carriage to vary the amplitude and range of movement of said latch wedges.
